United States Patent Office

Des. 210,534

Patented Mar. 19, 1968

210,534

MAGNETIC DATA STORAGE UNIT

Harold L. Dean, Wellesley, Mass., George H. Kress, East Orange, N.J., and Robert T. Pearson, Beverly, and David F. Sweeney, Wellesley, Mass., assignors, by mesne assignments, to Mohawk Data Science Corporation, Herkimer, N.Y., a corporation of New York

Filed Apr. 14, 1966, Ser. No. 1,900

Term of patent 14 years

(Cl. D26—5)

FIG. 1

FIG. 2

FIG. 3

FIG. 1 is a perspective view of the magnetic data storage unit showing our new design.

FIG. 2 is a top plan view thereof; and

FIG. 3 is a front elevation view thereof.

The dominant features of our design reside in the portions shown in full lines.

We claim:

The ornamental design for magnetic data storage unit, as shown and described.
